DISPENSING MACHINE

Aldo R. Curioni, New York, N. Y., assignor to
Sarioni Company, Inc., New York, N. Y., a corporation of New York

Application January 23, 1946, Serial No. 642,970

8 Claims. (Cl. 198—53)

1

The present invention relates to means for aligning and dispensing definite portions of fragile, slender articles such as macaroni or spaghetti.

Macaroni and spaghetti are generally sold to housewives in cardboard cartons or packages containing approximately one pound of the spaghetti or macaroni. The packaging of these particular foods is an item of considerable expense for the long thin sticks must first be aligned so that their axes are all substantially parallel with each other and thereafter the slender sticks or rods must be placed on weighing scales to form portions of the particular desired weight. Performing these operations manually is tedious, expensive, and objectionable for sanitary reasons. The utilization of machinery for grouping the sticks into portions of desired quantity presents the difficulty of aligning the sticks and grouping them into portions without excessive breakage. The macaroni and spaghetti sticks are quite fragile or brittle and snap into pieces if roughly handled; housewives object strongly to purchasing packages of macaroni or spaghetti and finding the sticks broken into short pieces upon opening of the packages.

The present invention aims to minimize or overcome the above and other difficulties and to provide a machine for automatically aligning and dispensing desired quantities of macaroni or spaghetti in readiness for packaging.

An object of the present invention is to provide a means and construction adapted to automatically dispense bundles of macaroni or spaghetti ready for packaging.

Another object of the invention is to provide means for automatically aligning slender articles such as macaroni.

Another object of the invention is to provide a new and improved means adapted to automatically weigh out desired portions of macaroni.

Still another object of the invention is to provide a means or construction adapted to facilitate and maintain alignment of spaghetti and macaroni during its movement through said means or construction.

A still further object of the invention is to provide means adapted to intermittently delay the flow of macaroni or spaghetti through a dispensing machine during intervals when the machine is dispensing a predetermined portion thereof.

Other and further objects of the invention will be obvious upon an understanding of the illustrative embodiment about to be described, or will be indicated in the appended claims, and various

2

advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is an elevational view showing one end of the present machine;

Fig. 2 is a side elevational view of the present machine;

Fig. 3 is an enlarged sectional view taken along the line 3—3 of Fig. 1; and

Fig. 4 is a sectional view showing means for movably supporting a part of the machine.

In the ensuing description of the present machine and its operation the terms macaroni and spaghetti will be frequently used. The use of the machine is not limited specifically to spaghetti or macaroni but these two terms are used for illustrative purposes; the machine is equally adaptable to aligning and dispensing food products such as vermicelli or other articles not utilized for food, such as slender lengths of glass tubing or the like.

Described generally, the present invention provides a machine adapted to receive slender sticks of spaghetti or macaroni and bring them into alignment so that their longitudinal axes are substantially parallel to each other, to transfer the sticks of macaroni in aligned relationship to a hopper or receptacle, and to effect removal of definite predetermined quantities of the spaghetti or macaroni from the hopper or receptacle.

Referring again to the drawings and more particularly to Figs. 2 and 3 thereof, the machine of the present invention is illustrated supported on legs 1 which are mounted on a suitable base or platform 2. Most of the operating parts of the present invention are carried by or between two spaced right hand and left hand side members or plates 4 and 5, the side plates being secured by bolts 7 or other appropriate means to the upper parts of the supporting legs 1, and being maintained in spaced relationship by studs or rods 8.

An initial requirement in preparing the spaghetti or macaroni in accordance with the present invention is to bring the slender lengths of material, as received from drying racks, into aligned relationship. This aligning process is commenced by the downwardly inclined members or surfaces 10 and 11 which form, together with the side walls or plates 4 and 5, a hopper or

trough 12. Spaghetti placed into this hopper 12 is supported by the members 10 and 11 which form a V-shaped bottom for the trough or hopper. The inclined members 10 and 11 are spaced from each other adjacent their lower ends to provide an exit opening 13 from the hopper. It is desired that the macaroni emerge from the exit opening 13 in substantially parallel relationship and this alignment is achieved by causing the member 11 forming one sloping wall of the hopper to oscillate to and fro as indicated by the arrow thereon; oscillation or vibration of this wall 11, as indicated, jiggles or vibrates the long slender macaroni sticks piled thereon so that they gradually work downwardly toward the exit 13 of this hopper and swing about until they lie substantially parallel to the opening 13. In this position they may gradually feed through the opening 13. The oscillatory motion of the plate or wall 11 is imparted to it by an electric driving motor (not shown) through the intermediate of a chain or belt drive 14, sprocket 16 mounted on the shaft 26, shaft 26 and eccentrically mounted arm or rod 21 which is secured adjacent one end thereof to the shaft 28 that supports one end of the downwardly inclined member 11. As the shaft 26 rotates, the eccentric rod oscillates rapidly to and fro; since the opposite end of the eccentric rod is mounted upon a cross shaft 28 which also carries the inclined plate member 11, the plate member 11 is caused to oscillate to and fro. Movement of the plate member 11 is facilitated by mounting the cross shafts 28 and 32 which support it upon spaced legs 29 and 31, the lower ends of the spaced legs 29 and 31 being carried by additional shafts 34 and 35. This construction provides a parallelogram arrangement which permits movement of the table to and fro in accordance with motion imparted to it by the eccentric rod 27.

The parallelogram legs 31 (Fig. 4) may be extensions from a sleeve member 36, carried upon the shaft 35, are preferably provided with bearing surfaces and are mounted upon the cross shafts 32 and 35 so that they may rotate with respect thereto. The parallelogram legs 29 located adjacent the lower end of the inclined member 11 are provided with bearing surfaces at their upper ends similar to the construction illustrated in Fig. 4 so that they may rotate with respect to the cross shaft 28, however, the lower ends of these parallelogram legs are preferably rigidly secured to the cross shaft 34 so that as the parallelogram legs move to and fro under the influence of the eccentric rod 27 the cross shaft 34 will also be rotated. The reason for rotating this cross shaft to and fro is to provide a source of power for operating other parts of the machine to be hereinafter described. In order to clarify future descriptions of operating parts, the driving force will be considered as the cross shaft 34 and motion will be traced back to it rather than to the drive chain 14.

As the sticks of macaroni or spaghetti emerge from the opening 13 they come into contact with, and are moved from beneath the opening by, a conveyor belt 37. The conveyor belt is shown in Fig. 3 as moving from right to left and the sticks of macaroni will also be carried in this direction. The sticks of spaghetti or macaroni are prevented from moving backwardly beneath the oscillating inclined member 11 by a flexible member 38 connected at one side with the lower end of the inclined oscillating plate member 11 and extending over a support 40 so that the free end 41 thereof

is located adjacent the moving conveyor belt 37. This flexible member 38 does not interfere with movement of the plate member 11 but minimizes movement of sticks of macaroni backwardly along the conveyor belt 37 and beneath the inclined member 11.

The conveyor belt 37 is carried upon and over a driving pulley or roller 43 mounted upon the shaft 17 and over a driven pulley or roller 45. The driving roller 43 and cross shaft 17 are rotated by the sprocket 16 previously referred to through the intermediate of shaft 26, gear 25, forty-five degree angle gear 23, shaft 22, worm gear 20, and gear 19. This construction also acts as a speed reducer so that the belt 37 will move at desired speed. Tensioning rollers 46 and 47 are provided for minimizing the occurrence of slack in the conveyor belt. The tensioning roller 46 is mounted upon a shaft or pins 48 and lever arms 49 and 50 are located adjacent the ends thereof, these lever arms being connected adjacent their lower ends with tension springs 51 and 52 that are in turn connected adjacent their other ends to threaded rods 54 and 55. The threaded rods 54 and 55 extend through projections or lugs 57 and 58 carried by the side plates 4 and 5, and may be adjusted longitudinally to vary the amount of spring tension by means of nuts 60 and 61. The springs 51 and 52 continually urge the lower ends 30 of the lever arms 49 and 50 toward the left and thus cause the upper ends thereof to press against the shaft 53 of the upper tensioning roller 47; the shaft of this upper tensioning roller 47 is carried in angularly disposed or inclined slots 62 of members 64 secured to the side plates 4 and 5 and the effect of the pressure applied by the upper end of the lever arm is to force the upper tensioning roller downwardly firmly against the upper surface of the conveyor belt 37. This construction effectively minimizes the occurrence of slack in the conveyor belt.

The volume or quantity of transversely disposed sticks of macaroni or spaghetti carried away from the opening 13 by the conveyor belt 37 may be controlled by elevating or lowering the inclined side 10 of the V-shaped spaghetti-receiving hopper 12. Longitudinal movement of this inclined side 10 may be obtained by rotating an adjusting screw 65 carried on a cross bar secured to the upper parts of the side plates 4 and 5. The adjusting screw 65 is threaded into a nut 67 attached to the inclined side 10 and thereby raises or lowers it to control the effective size of the opening 68, between the lower end thereof and the upper surface of the conveyor belt. The lower end of this inclined side member 10 thus operates as a gate, the position of which may be varied to admit sticks of different sizes or to control the quantity of material passing out of the opening 13 and along the conveyor belt 37. This feature is desirable in securing uniform movement or flow of transversely disposed sticks of macaroni along with the belt and through the machine; it tends to spread the slender sticks evenly over the surface of the belt.

In order to further insure against piling up of macaroni sticks along the belt and to obtain a more uniform distribution of material on the belt 37 a vibrating shoe 70 is utilized to agitate the material as it arrives at the belt from the opening 13. The shoe 70 may have a wearing surface 71 attached to the shoe proper and the shoe is preferably fastened to a cross shaft 73 that oscillates rapidly to and fro under the in-

fluence of the cross shaft 34 through the inter-mediation of lever 74, connecting rod 75, and lever 76. The last three mentioned parts are shown more clearly in Fig. 2 of the drawings. Rapidly jiggling or vibrating of the conveyor belt 37 by the shoe 70 tends to shake the slender sticks of macaroni or spaghetti down into an evenly disposed layers or layers as the belt and macaroni pass over the surface of the shoe 70.

To still further facilitate distribution and passage of the slender sticks of macaroni or spaghetti in substantially contiguous relationship and uniform layer or layers along the belt and through the machine, there is utilized an oscillating barrier or gate 78 which moves rapidly up and down with respect to the moving belt 37. The gate 78 is shown in Fig. 3, located above the conveyor belt and beyond the shoe 70, being carried by spaced arms 79 of a sleeve 71 mounted on the shaft 80. An oscillating or rocking motion is imparted to the shaft 80 (Fig. 2) and gate 78 by the cross shaft 34 through inter-mediation of lever 74, connecting rod 75, lever 76, connecting rod 81, and lever arm 82 clamped to the shaft 80 by a nut and bolt 83. It is preferred that a torsion spring 84 be used to urge the arm 79 and gate 78 into downward position; the various actuating levers and shafts impose their lifting action in opposition to the effect of the spring 84. Movement of the gate 78 rapidly up and down to open and close the passage through which the material passes as it moves along with the conveyor belt 37 tends to smooth out irregularities which may occur in the distribution of the material along the belt and to separate pieces of spaghetti which may have become accidentally stuck together during previous manufacturing operations.

In certain instances, for example in utilizing a machine in connection with packaging slender articles of different diameters such as spaghetti, macaroni or vermicelli, it is desirable to change the amplitude of the oscillation of the gate member 78. Fig. 2 illustrates a means for accomplishing this. A screw member or bolt 86 threaded into a nut or clamp 87 bolted to the side member 4 of the machine is provided with spaced lugs or projections 88 adapted to receive between them one end 89 of a pivoted bell crank 91. The other end 92 of the bell crank 91 is connected with one end of a rod 94, the other end of this rod 94 being connected adjacent one end of the connecting rod 81 that moves the gate member 78 through the lever arm 82 and shaft 80. The connecting rod 81 moves to and fro as indicated generally by the arrow thereon. Screwing the bolt 86 in or out of a nut 87 is effective to shift the position of the spaced lugs 88 and the end 89 of bell crank 91, thus rotating the bell crank about its pivot. This causes upward and downward movement of the end 92 of the bell crank 91 and the connecting link 94 and thus shifts the position of the end of the rod 81 which actuates the shaft 80 and gate member 78. When the contact point between the end of the connecting rod 81 and the lever arm 82 is adjacent the outer or free end of the lever arm 82 a small motion of the oscillating gate member 78 will be obtained and when the contact point is close to the inner end of lever arm 82 the gate 78 will be moved to a greater degree. This difference in motion is obtained by virtue of the fact that even though the amplitude of movement of the connecting rod 81 remains substantially constant, the length of the lever arm 82

through which this motion is transmitted to the shaft 80 is changed to vary the movement of the gate 78.

The combination of natural gravity flow of spaghetti or macaroni through the opening 13, movement beneath the adjustable gate 10, over vibrating shoe 70 and past the oscillating gate 78 is effective to spread the slender and fragile sticks evenly along the belt and to provide even flow and delivery of the material by the belt. The agitating or shaking and smoothing of the various parts is sufficient to facilitate even distribution and smooth flow of material yet it is not so rough as to cause objectionable breakage of the slender and fragile sticks of material.

As the spaghetti leaves the end of the belt 31 it is caught by a shelf or tray 95 interposed between the belt 37 and a receptacle or hopper 85 adapted to receive the spaghetti sticks. The shelf or tray-like structure 95 minimizes the possibility of macaroni sticks twisting about upon leaving the belt 37 and falling with their axes vertically disposed; it maintains their axes substantially parallel. The shelf 95 also minimizes breakage of the fragile material as it passes from the conveyor to the hopper 85. The shelf 95 is shown secured to a shaft 97 which preferably oscillates so as to move the shelf 95 up and down as indicated by the arrow thereon. The shaft 97 which carries this shelf is caused to oscillate or rock about its axis by picking up movement from the same lever arm 76 which vibrates the shoe 70; connecting rod 98 transfers motion from lever arm 76 to lever arm 100, which is clamped to the shaft 97 by a nut and bolt 101 (Fig. 2). The rocking motion of this shelf or tray 95 reduces the possibility of sticks of material accidentally piling up similarly to a mass of logs in a log jamb. The sticks drop off the end of the conveyor 37 into the rocking shelf 95, roll along the moving shelf, and drop off the edge thereof onto an inclined chute 103, roll down the chute past the gate 104, which will be open as indicated by the dotted lines; and into the elongated receptacle 85.

It should be noted (Fig. 3) that when the stream of macaroni is flowing into the receptacle 85 the door 119 and the intermediate stop member 104 are in the positions indicated by dotted lines. That is, the intermediate stop 104 is open and the receptacle door 119 is closed. These two parts and their features will be hereinafter described.

The elongated receptacle or hopper 85 is carried on an arm or post 105 which is connected to a scale 106 for weighing the contents of the hopper. The weighing scale is of conventional commercially available type and the constructional and operational details thereof will not be described herein. When a definite predetermined quantity of macaroni or spaghetti has been received in the elongated hopper 85 it is desirable that the hopper be emptied and prepared to receive an additional quantity of material. This feature is achieved as follows: Connected with the same post or arm 105 which carries the hopper 85 and actuated by movement of the hopper and this post, is a bar or lever 107 supported on a fulcrum 108 intermediate the ends thereof. The free end of the lever 107 is provided with an electrical contact 109 adapted to touch another electrical contact 110 carried by an arm 111, both of the contact points being connected with an electrical circuit indicated by the wires 113 and 114. When the contact points

109 and 110 are together, due to the entry of sufficient weight of macaroni into the elongated receptacle 85, an electrical circuit is closed and current flows through the circuit. The wires 113 and 114 are joined to connections of a solenoid 118 which actuates a mechanism for controlling the opening and closing of a hopper door 119 and the intermediate gate 104. When the contacts 109 and 110 are closed and the circuit energized a link or rod 120 is moved by the core of the solenoid to operate the gate 104 and door 119 controlling mechanism shown at the left of Fig. 3. When the circuit is energized current flows through the coils of the solenoid 118 and the rod 120 is moved upwardly approximately one inch. The component parts of the electrical circuit and its hook-up are of conventional type and will not be described in detail herein. The lower end of the link 120 is secured by a pin 121 to a cam 122 and upward movement of the link 120 rotates the operating cam 122 and sleeve 123 about shaft 125 in clockwise direction, in opposition to torsion springs 126 which tend to maintain the cam 122 and link 123 in downward position. The use of the torsion springs 126 is optional as will be shown from later descriptions. Riding against and actuated by the cam surfaces are a pin 127 connected to means for operating the intermediate gate 104, and a roller 128 connected with means for operating the door 119 of the hopper 85.

When the solenoid link 120 is located in its downward position the cam 122 is so positioned that the pin 127 carried by the extension 129 of the pivoted intermediate gate member 104 is in contact with the surface of the cam. A spring 130 secured to the extension of the pivoted intermediate gate 104 and to the framework of the machine pulls the pin 127 firmly against the cam surface; with the solenoid link in its downward position the cam surface is effective to hold the pin 127 and gate extension 129 to the right in opposition to the tension of the spring 130 and to thus maintain the opposite gate portion 104 in open position so that sticks of macaroni or spaghetti may pass from the inclined chute 103 into receptacle 85. When the solenoid link 120 is moved upwardly the cam 122 is rotated in a clockwise direction and the spring 130 pulls the extension 129 of the gate 104 against the retreating surface of the cam. The surface of the cam is so designed so that it eventually moves out of contact with the pin 127 and the spring 130, tending to rotate the intermediate member about the shaft 131 in a counter-clockwise direction, causes the lower end of the gate to abut against the lower edge of the inclined chute 103; this stops the flow of material along the chute and into the hopper.

When the solenoid link 120 is in its lowermost position the intermediate gate 104 is open and the cam roller 128 is in contact with a high point or area of the cam 122. In this relationship the lever 133, link 134 and lever 135 are in their lowermost or closed position as indicated by the dotted positions of Fig. 3. At such time the free end of the lever 135 is out of contact with the extension 137 of the hopper door 119 and the door 119 which is carried by the arm 138 secured to pivots 139, is closed due to the effect of gravity. As the cam 122 rotates in a clockwise direction the roller 128 rides along the high surface of the cam until it reaches the cutaway portion thereof and then moves radially inwardly toward the center of the cam. Spiral torsion springs 140

extending about the sleeve 141 and shaft 142 and secured to the lever 133 and framework of the machine cause the roller to press firmly against the cam and hence move inwardly along the cut-away surface of the cam. Movement of the roller 128 along the cutaway surface of the cam lifts the end of lever 133, the link 134 and lever 135 upwardly, the free end of the lever 135 moving into contact with the extension 137 of the pivoted hopper door 119 to thereby lift the door and allow marcaroni to roll out of the hopper into a pan or tray 143. The macaroni may be removed manually from the pan and packaged or placed on a conveyor. The pan 143 is intended to illustrate generally means for receiving measured portions of aligned macaroni or spaghetti; in actual practice the measured portions are preferably guided directly into waiting boxes or other containers which are automatically moved beneath and away from the receptacle 85 and any appropriate chute.

It should be noted that the cam 122 and the members operatively connecting the cam with the hopper door 119 and intermediate gate 104 are so constructed that the gate 104 is closed prior to opening of the hopper door 119, and that the hopper door 119 is closed prior to opening of the intermediate gate 104; the cam 122 actuates the door and intermediate gate in timed relation with respect to each other. This is important for the conveyor belt 37 and large hopper 12 are continually operating to align and transfer sticks of material to the inclined chute 103. In the event the flow of material from the belt 37 and rocking tray 95 continued uninterruptedly during intervals when the hopper 85 was being emptied it would be difficult or impossible to accurately dispense correct weights of material in each instance for packaging.

The operation of the mechanism for controlling the gate 104 and door 119 may be tested manually, or the mechanism may be operated manually in emergencies by providing a manually operable handle or lever 145 pivoted at 146 intermediate its ends to the frame of the machine and at its free end 147 to the solenoid link 120. Movement of the handle up and down lifts or lowers the solenoid link 120 and thus actuates the controlling mechanisms. A spring 148 may be utilized to urge the manual lever and solenoid link into downward position.

To put the machine into action the driving motor (not shown) is first started. When the motor has been started and the drive chain or belt 14 is revolving to rotate the sprocket and operate the machine, long slender sticks of fragile macaroni, spaghetti or the like may be placed into the large hopper 12 located at the upper part of the machine. The oscillatory or shaking motion of the downwardly inclined surface 11 vibrates or shakes the macaroni so that it gradually becomes transversely disposed and moves down toward the bottom of the hopper 12 to emerge from the opening 13 at the lower part thereof. The aligned slender sticks are then picked up by the moving conveyor belt 37 and carried beneath the end of the adjustable gate 10, the gate tending to control the flow of admission of the sticks out of the exit 13 and along with the conveyor belt 37. Adjacent to the lower end of the gate 10 the belt 37 passes over a vibrating or agitating shoe 70 which shakes the belt to form sticks of material into a substantially uniform layer or layers. The macaroni is carried along by the moving conveyor belt and

reaches the oscillating gate 78, the action of which is to further iron out or smooth irregularities that may occur in the distribution of the macaroni along the belt 37 and to separate sticks of material which may be adhered together. From the conveyor belt the sticks of material pass onto a rocking plate or shelf 95, the shelf maintaining the parallelism of macaroni and minimizing breakage thereof by allowing the sticks to roll off the end of the shelf onto a downwardly inclined chute 103. The aligned sticks of macaroni pass along the chute 103, through the open gate 104 and into an elongated hopper 85. The door of the hopper 85 is closed and the sticks of macaroni continue to accumulate therein until a predetermined weight sufficient to move the arm or post 105 of the scale 106 downwardly slightly is accumulated in the hopper. As the hopper and post move downwardly a lever arm 107 mounted on a fulcrum 108 closes electrical contacts 109 and 110 and energizes the circuit of a solenoid 118 that actuates the mechanisms for controlling movements of the intermediate gate 104 and hopper door 119. When the electrical circuit is energized a solenoid link or rod 120 moves upwardly to rotate an operating cam 122 in clockwise direction. This clockwise rotation of the cam 122 first effects closing of the gate 104 against the lower end of the inclined chute 103, thereby cutting off the flow of macaroni entering the hopper 85, and immediately thereafter opens the door 119 of the elongated hopper. The aligned sticks of macaroni flow out of the hopper 85 into a collecting chute and receiving means such as tray 143 or the package itself. As the emptied hopper 85 returns to the upper position the electrical contacts 109 and 110 are opened and the electrical circuit and the coils of the solenoid 118 are de-energized. De-energizing the circuit allows the solenoid link 120 to move downwardly under the influence of the springs 126 and 148 secured to the sleeve 123 and handle 145, respectively. The normal influence of these springs is to urge the solenoid link 120 downwardly in opposition to the magnetic influence of the solenoid coils. Rotation of the cam in a counter-clockwise direction first causes closing of the hopper door 119 and immediately thereafter effects opening of the intermediate gate 104, allowing the macaroni sticks to again flow into the hopper 85. The operation of the machine is continuous and as long as spaghetti or macaroni is fed into the large open hopper 12 there will be portions of definite quantity issuing from the delivery end of the machine. The large hopper 12 and various transfer mechanisms line up the spaghetti and maintain the alignment thereof during movement through the machine; the combination of smaller elongated hopper 85 and scale mechanisms receive the aligned macaroni and dispense it in predetermined portions. The mechanisms cooperate to deliver desired portions of spaghetti or macaroni ready for packaging.

It will be seen that the present invention provides a machine for aligning and dispensing definite predetermined portions of slender fragile, rod-like material such as spaghetti or macaroni. The machine is automatic and rapid in operation and eliminates numerous steps that are extremely tedious and which increase packaging costs when performed manually. The elimination of numerous manual operations is most desirable for sanitary reasons. The aligning and dispensing is achieved with a minimum amount of break-

age. Numerous parts may be constructed from light, strong metal such as aluminum, which makes for a strong and light weight machine. The machine is sturdy in construction and well able to withstand any rough usage to which it may be subjected.

As various changes may be made in the form construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a machine of the class described adapted to provide a substantially uniform stream of material, the combination of a hopper including an oscillatable bottom wall and an end wall movable toward and away from said bottom wall, said walls being normally spaced apart to provide a discharge opening, leg members supporting said bottom wall at spaced locations, means supporting said leg members at locations spaced from said bottom wall, means for moving said leg members to and fro to thereby oscillate said bottom wall and move material toward and through said discharge opening, transferring means below said discharge opening for transferring from the discharge opening material delivered therethrough, a guide member below said transferring means for guiding material toward a receiving compartment, and an oscillatable member having a portion extending beneath said transferring means and above said guide member for receiving material from the transferring means and lowering it toward the guide member.
2. In a machine of the class described adapted to provide a substantially uniform stream of material, the combination of a hopper including an oscillatable bottom wall and an end wall movable toward and away from said bottom wall, said walls being normally spaced apart to provide a discharge opening, leg members supporting said bottom wall at spaced locations, means supporting said leg members at locations spaced from said bottom wall, means for moving said leg members to and fro to thereby oscillate said bottom wall and move material toward and through said discharge opening, transferring means below said discharge opening for transferring from the discharge opening material delivered therethrough, a guide member below said transferring means for guiding material toward a receiving compartment, an oscillatable member, having a portion extending beneath said transferring means and above said guide member for receiving material from the transferring means and lowering it toward the guide member, and means operatively interconnecting said oscillatable member with the leg member moving means for actuating the latter with the former.

3. In a machine of the class described adapted to provide a substantially uniform stream of material, the combination of a hopper including an oscillatable bottom wall and an end wall movable toward and away from said bottom wall, said walls being normally spaced apart to provide a discharge opening, leg members supporting said bottom wall at spaced locations, means supporting said leg members at locations spaced from said bottom wall, means for moving said leg members to and fro to thereby oscillate said bottom wall and move material toward and through said discharge opening, transferring means below said discharge opening for transferring from the discharge opening

discharge opening material delivered therethrough, a member above said transferring means reciprocable toward and away therefrom for smoothing out material being transferred, a guide member below said transferring means for guiding material toward a receiving compartment, and an oscillatable member having a portion extending beneath said transferring means and above said guide member for receiving material from the transferring means and lowering it toward the guide member.

4. A machine as claimed in claim 3, in which means is provided for selectively varying the amount of movement of the member which reciprocates toward and away from the transferring means.

5. In a machine of the class described adapted to provide a substantially uniform stream of material, the combination of a hopper including an oscillatable bottom wall and an end wall movable toward and away from said bottom wall, said walls being normally spaced apart to provide a discharge opening, leg members supporting said bottom wall at spaced locations, means supporting said leg members at locations spaced from said bottom wall, means for moving said leg members to and fro to thereby oscillate said bottom wall and move material toward and through said discharge opening, transferring means below said discharge opening for transferring from the discharge opening material delivered therethrough, means adjacent said discharge opening for agitating said transferring means to smooth out materials thereon, a guide member below said transferring means for guiding material toward a receiving compartment, and an oscillatable member having a portion extending beneath said transferring means and above said guide member for receiving material from the transferring means and lowering it toward the guide member.

6. A machine as claimed in claim 1, in which said transferring means is upwardly inclined from a location adjacent said discharge opening to a location adjacent said oscillatable member.

7. In a machine of the class described adapted to deliver a plurality of substantially equal batches of material, the combination of a hopper including an oscillatable bottom wall and an end wall movable toward and away from said bottom wall, said walls being normally spaced apart to provide a discharge opening, leg members supporting said bottom wall at spaced locations, means supporting said leg members at locations spaced from said bottom wall, means for moving said leg members to and fro to thereby oscillate said bottom wall and move material toward and through said discharge opening, transferring means below said discharge opening for transferring from the discharge opening material delivered therethrough, a guide member below said transferring means for guiding material toward

a receiving compartment, an oscillatable member having a portion extending beneath said transferring means and above said guide member for receiving material from the transferring means and lowering it toward the guide member, and means for intermittently blocking and releasing material moving along said guide member.

8. In a machine of the class described adapted to provide a substantially uniform stream of material, the combination of a hopper including an oscillatable bottom wall and an end wall movable toward and away from said bottom wall, said walls being normally spaced apart to provide a discharge opening, leg members supporting said bottom wall at spaced locations, means supporting said leg members at locations spaced from said bottom wall, means for moving said leg members to and fro to thereby oscillate said bottom wall and move material toward and through said discharge opening, transferring means below said discharge opening for transferring from the discharge opening material delivered therethrough, a guide member below said transferring means for guiding material toward a receiving compartment, an oscillatable member having a portion extending beneath said transferring means and above said guide member for receiving material from the transferring means and lowering it toward the guide member, means for intermittently blocking a stream of material moving along said guide member, a receiving compartment below said guide member for catching said stream of material when not blocked, and means for opening the receiving compartment when the stream of material is blocked.

ALDO R. CURONI.
